UNITED STATES PATENT OFFICE.

HENRY HENSCHEL, OF NEW YORK, N. Y., ASSIGNOR TO McLOUGHLIN BROTHERS, INC.,
OF NEW YORK, N. Y., A CORPORATION OF NEW YORK.

FOLDABLE FURNITURE.

1,283,762.

Specification of Letters Patent.

Patented Nov. 5, 1918.

Application filed May 24, 1918. Serial No. 236,278.

To all whom it may concern:

Be it known that I, HENRY HENSCHEL, a citizen of the United States, and a resident of the borough of Bronx, city and State of New York, have invented an Improvement in Foldable Furniture, of which the following is a specification.

My invention relates to toy articles of furniture, and particularly such as are intended to be cut out of sheets of foldable material, such as paper, for example, and afterward assembled in the desired form.

The object of my invention is to provide articles of the character designated, and also blanks for such articles, which shall be simple and convenient to manufacture and assemble, and which, when assembled, shall be rigid and durable in use, and pleasing and attractive in appearance.

By way of example I have illustrated several preferred embodiments of my invention in the accompanying drawings wherein:

Figure 1 is a plan view of a blank representing one embodiment of my invention and intended to reproduce, when assembled, an article simulating the appearance of a kitchen sink;

Fig. 2 is a longitudinal section of the same in assembled form;

Fig. 3 is a bottom plan view of the same;

Fig. 4 is a plan view of a blank constituting another embodiment of my invention and intended to simulate, when assembled, a chair;

Fig. 5 is a longitudinal section of the same in assembled form;

Fig. 6 is a bottom plan view of the same;

Fig. 7 is a plan view of a blank constituting another embodiment of my invention and intended to simulate, when assembled, a chair;

Fig. 8 is a plan view of a blank constituting still another embodiment of my invention and intended to simulate, when assembled, a tea wagon;

Fig. 9 is a cross section of the device shown in Fig. 2;

Fig. 10 is a similar view of the device shown in Fig. 5;

Figs. 11 and 12 are plan views of two blank portions constituting another embodiment of my invention;

Fig. 13 is a bottom plan view of the same; Fig. 14 is a longitudinal section, and

Fig. 15 is a cross section of the same;

Fig. 16 is a plan view of a blank constituting still another embodiment of my invention;

Fig. 17 is a bottom plan view of the same;

Fig. 18 is a longitudinal section, and

Fig. 19 is a cross-section of the same.

Referring to the illustrative embodiment shown in Figs. 1, 2, 3, and 9 of the drawing, the toy article of furniture therein illustrated may comprise, for example, a main portion 1 with which are associated a plurality, herein shown as three, portions for providing depending portions 2. In the form illustrated, the main portion 1 may have associated therewith an auxiliary member 1' for completing the configuration of the article when assembled.

Associated with the main portion 1 and the depending portions 2 are a plurality, herein shown as four in number, of members 3 for providing supporting members or legs for the article when in assembled form. In the embodiment illustrated in Figs. 1, 2 and 3, two of the supporting members 3 are associated with one of the depending portions 2, while the remaining two supporting members are each associated with one each of the remaining two depending portions 2. Preferably each supporting member 3 consists of a plurality of foldable portions 3'.

Associated with one or more, herein shown as two, of the depending portions 3, are a plurality of portions 4 for providing locking members. Locking members 4 are preferably provided with coöperating, opposed slots 4' or other suitable means for causing said members to engage or lock when the device is in assembled form. Associated with another of the depending portions 2 is a member 5 for providing retaining and binding means to position the supporting members associated with said last mentioned depending member 2. The retaining member 5 has a binding member 5' associated therewith.

In assembling the article to be made of the blank just described, the part 1' is bent upward until it is substantially at right angles to main portion 1. The depending portions 2 are all bent downwardly until

- substantially at right angles to main portion 1. The free members 3' are then bent at right angles to their associated members 3'. Locking members 4 are then bent at 5 right angles to their respective depending portions 2 so as to be substantially parallel to main portion 1, after which said members 4 are put in the locking position by bringing their opposed slots 4' together.
- 10 Retaining and binding member 5 is then bent so as to be substantially at right angles to its associated depending portion 2. This will make portion 5 substantially parallel to main portion 1 and the now locked 15 locking members 4. The retaining portion 5' is now bent so as to inclose locking members 4. For this purpose I prefer to make member 5' of a width substantially greater than, as twice as great as, the depth of the 20 associated depending member 2. In this way the binding member 5 and retaining member 5' are properly positioned and held in place to thereby properly position the associated depending portion 2 and the supporting members 3 carried thereby.
- The embodiment shown in Figs. 4, 5, 6 and 10 is substantially similar to the embodiment shown in Figs. 1, 2, 3, and 9, except that in this embodiment several of the 30 supporting members are provided with positioning members or portions in order to render the device more rigid and durable. The embodiment shown in Figs. 4, 5, 6, and 10 is intended to simulate, when assembled, 35 a chair. This embodiment comprises a main portion 11; an auxiliary portion 11'; depending portions 12; supporting members 13, each comprising a plurality of, as two, foldable portions 13'; locking members 14 40 provided with the opposed slots 14'; retaining member 15 and associate binding member 15', substantially as in the case of the analogous parts of the species already described.
- 45 One or more of the supporting members 3, herein shown as two such members, are provided with positioning members 16 which are preferably substantially at right angles to their associated supporting members 13.
- 50 In assembling the article to be made of the blank just described, parts 11, 11', 12, 13, 13', 14, 15 and 15' are manipulated as in the case of the analogous parts of the species first described. The principal difference in 55 the assembly of this device is that the free members 13' of supporting members 13 provided with positioning members 16 are so folded as to be within the depending portions 12 carrying the other supporting members 13. In this way the positioning members 16 will be brought to bear down against the locking members 14 and outwardly against the depending members 12 with which the remaining supporting members 13 60 are associated. This is due to the natural

tension or resistance to folding of the material of which the blanks and devices to be made therefrom are manufactured.

In Fig. 8 I have shown a form of blank constituting another embodiment of my invention similar in most respects to the embodiment illustrated in Figs. 4, 5, 6 and 10, and differing therefrom principally in that each supporting member 33 is provided with an associated positioning member 36. In 75 this species, moreover, binding and retaining means of the character shown in connection with the first three species herein described are not employed, since the extra positioning members act to properly position the various parts of the device made from the blank illustrated. It is moreover to be noted that in this form there are four depending members 32 associated with the main portion 31, two of the supporting members being associated with one of these depending members, and the other two supporting members being associated with the opposite depending member 32. In this species also each supporting member 33 comprises a plurality of foldable portions 33' with the outer or free one of which each positioning member 36 is associated.

In Fig. 7 I have shown still another form of blank constituting another embodiment 95 of my invention similar in most respects to the embodiment illustrated in Figs. 4, 5, 6, and 10, except that in this embodiment the locking members 37, 38 are of unequal length, a construction often rendered desirable in order to economize in the material employed for making the blank.

The manner of assembling the devices to be made of the blanks shown in Figs. 7 and 8 will be substantially clear from the foregoing description, especially those parts thereof relating to the manner of assembling the devices made of the blanks shown in connection with the first two species above described.

In Figs. 11, 12, 13, 14, and 15 I have illustrated another embodiment of my invention which is similar in most respects to the embodiment illustrated in Figs. 1, 2, 3, and 9 of the drawing. The principal point of difference is that in the embodiment under consideration the locking members comprise not solely two members, integral or otherwise attached to the main portion of the blank, but preferably a plurality of short 120 locking members 38 and 39, rigidly attached to the main blank portion 40, as by being made integral therewith, and provided with the respective slots 41 and 42 which open in the same direction.

I provide also a separable locking member 43 provided with a pair of slots 44 and 45 which coöperate with slots 41 and 42 of members 38 and 39, respectively. The various slots 41, 42, 44 and 45 are so oriented 130

and positioned that binding member 46 and retaining portion 47, when folded into the positions more clearly shown in Fig. 15, will help to maintain independent locking member 43 in locking engagement with locking members 41 and 42. In this embodiment I have also shown positioning members 48 and 49 for the purpose already set forth in connection with the species shown in Figs. 4, 5, 10, 6, and 10, although other positioning means, such as the notches illustrated in connection with the species shown in Figs. 16, 17, 18, and 19, may be employed.

Referring to the embodiment illustrated in Figs. 16, 17, 18, and 19, the same may comprise a main blank portion 50 with which are associated a plurality, herein shown as three, parts for providing depending portions 51. In the form illustrated, main portion 50 may have associated therewith an auxiliary member 52 for completing the configuration of the article when assembled.

Associated with main portion 50 and depending portions 51 are a plurality, herein shown as four, members 53 for providing supporting members or legs for the article when in assembled form. In the embodiment under consideration, two of the supporting members 53 are associated with one 25 of the depending portions 51, while the remaining two supporting members are associated with one each of the remaining two depending portions 51. Preferably each supporting member 53 comprises a plurality 30 of foldable portions 53'.

Associated with one or more, herein shown as two, of the depending portions 51, are a plurality of locking members 54. These locking members are preferably comparatively short members provided with respective slots 55 which preferably face in the same direction. With the remaining dependent portion 51 is associated a locking and binding member 56, provided with a 40 plurality of cut away portions 57 and the tabs or projections 58 provided with the respective slots 59 for coöperating with slots 55. While positioning members similar to the members 48 and 49 of the species illustrated in Figs. 11, 12, 13, 14, and 15 may be employed, I prefer to employ the positioning means illustrated, comprising a plurality of notches 60 and 61 for coöperating with the respective locking members 54 45 when the device is assembled.

The manner of assembling the species just described will be substantially clear from the foregoing description. In assembling the device of this embodiment, part 52 is 50 bent upward until it is substantially at right angles to main portion 50. The depending portions 51 are all bent downwardly until substantially at right angles to main portion 50. The free members 53' are 55 bent at right angles to their associated mem-

bers 53'. Locking members 54 are then bent at right angles to their respective depending portions 51, so as to be substantially parallel and underneath main portion 50, after which slots 59 are brought into locking engagement with slots 55 and supporting members 53 are so manipulated as to bring notches 60 and 61 into binding engagement with respective locking members 54.

It is of course to be understood that my invention is not to be limited to the specific embodiments herein shown by way of example merely.

What I claim is:

1. A foldable blank for toy articles of furniture, comprising a main portion, a plurality of portions associated with said main portion for providing depending portions, a plurality of members associated with said depending portions for providing supporting members, a plurality of members associated with at least two of said depending portions for providing locking members, and a member associated with another of said depending portions for providing retaining and binding means.

2. A foldable blank for toy articles of furniture, comprising a main portion, a plurality of portions associated with said main portion for providing depending portions, a plurality of members associated with said depending portions for providing supporting members, a plurality of members associated with at least two of said depending portions for providing locking members, and members associated with one or more of said supporting members for providing one or more positioning members for said supporting members.

3. A foldable blank for toy articles of furniture, comprising a main portion, a plurality of portions associated with said main portion for providing depending portions, a plurality of members associated with said depending portions for providing supporting members, a plurality of members associated with at least two of said depending portions for providing locking members, a member associated with another of said depending portions for providing retaining and binding means, and members associated with one or more of said supporting members for providing one or more positioning members for said supporting members.

4. A toy article of furniture comprising a main portion, a plurality of depending portions associated with said main portion, a plurality of supporting members associated with said depending portions, a plurality of locking members associated with at least two of said depending portions, and a retaining and binding member associated with another of said depending portions and coöperating with said locking members for positioning certain of said supporting members.

5. A toy article of furniture comprising a main portion, a plurality of depending portions associated with said main portion, a plurality of supporting members associated with said depending portions, a plurality of locking members associated with at least two of said depending portions, and one or more positioning members associated with one or more of said supporting members and co-operating with said locking members and certain of said depending portions for positioning certain of said supporting members. 6. A toy article of furniture comprising a main portion, a plurality of depending portions associated with said main portion, a plurality of supporting members associated with said depending portions, a plurality of locking members associated with at least two of said depending portions, a retaining and binding member associated with another of said depending portions and co-operating with said locking members for positioning certain of said supporting members, and a member associated with one or more of said supporting members for providing one or more positioning members for said supporting members.
7. A foldable blank for toy articles of furniture, comprising a main portion, a plurality of portions associated with said main portion for providing depending portions, a plurality of members associated with said depending portions for providing supporting members, one or more members associated with one or more of said depending portions for providing locking means, and a member associated with another of said depending portions for providing retaining and binding means.
8. A foldable blank for toy articles of furniture, comprising a main portion, a plurality of portions associated with said main portion for providing depending portions, a plurality of members associated with said depending portions for providing supporting members, one or more members associated with one or more of said depending portions for providing locking means, and members associated with one or more of said supporting members for providing one or more positioning members for said supporting members.

In testimony whereof, I have signed my name to this specification this 22nd day of May, 1918.

HENRY HENSCHEL.
